UNITED STATES PATENT OFFICE

95,179

DESIGN FOR A MATTRESS COVER

James Reid Johnson, New London, Conn.

Application February 27, 1935, Serial No. 55,633

Term of patent 7 years

To all whom it may concern:

Be it known that I, James Reid Johnson, a citizen of the United States, residing at No. 95 Garden Avenue, New London, in the county of New London, and State of Connecticut, have invented a new, original, and ornamental Design for Mattress Covers, of which the following is a specification, reference being had to the accompanying drawing, forming part thereof.

The figure is a plan view of a mattress cover showing in detail one-quarter of the design, the

other three complementary quarters being of the same pattern, so that when they are assembled a complete, unitary, rectangular, oblong design is produced; portions of the mattress cover are shown as broken away to save space, and to permit showing the pattern on a larger scale than would otherwise be practicable.

I claim:

The ornamental design for a mattress cover, as shown and described.

JAMES REID JOHNSON.
